UNITED STATES PATENT OFFICE.

IRA A. BURNETT, OF CHICAGO, ILLINOIS.

EQUESTRIAN TOY VEHICLE.

1,345,578.

Specification of Letters Patent.

Patented July 6, 1920.

Application filed December 8, 1919. Serial No. 342,159.

To all whom it may concern:

Be it known that I, IRA A. BURNETT, a citizen of the United States, residing at Chicago, in the county of Cook and State of Illinois, have invented certain new and useful Improvements in Equestrian Toy Vehicles, of which the following is a specification.

This invention relates to improvements in 10 a toy of an equestrian or hobby-horse type, and it consists in certain peculiarities of the construction, novel arrangement, combination and operation of the various parts thereof as will be hereinafter more fully 15 set forth and specifically claimed.

The principal object of the invention is to 20 provide a riding toy or vehicle in the form of a miniature horse or pony mounted on a wheeled frame, which can be propelled and steered by a child sitting astride the body 25 of the horse, the legs and head of which will be caused, in the propulsion of the vehicle, to move in a life like manner, or natural way, the simulation of the speed at which the animal appears to be traveling being indicated by the rapidity of the movement of its legs, which movement is caused and regulated by the rider.

Another object of the invention is to 30 provide means whereby the device can be economically made, the parts easily assembled and the major portion of the propelling mechanism thereof housed or inclosed, to the end that liability of the child being injured thereby, or its clothes becoming entangled therewith will be reduced to a minimum.

Other objects and advantages of the invention will be disclosed in the following 40 explanation and description.

In the accompanying drawings, which serve to illustrate an embodiment of the invention—

Figure 1 is a view in side elevation of the 45 toy vehicle showing the legs of the horse in one of the positions they will assume in the movement of the vehicle.

Fig. 2 is a central vertical sectional view 50 through the body of the horse taken on line 2—2 of Fig. 3 looking in the direction indicated by the arrows but showing the supporting frame in elevation.

Fig. 3 is a plan sectional view taken on line 3—3 of Fig. 2 looking in the direction indicated by the arrows.

Fig. 4 is a cross-sectional view taken on

line 4—4 of Fig. 3 looking in the direction indicated by the arrows.

Fig. 5 is a vertical view partly in section and partly in elevation taken on line 2—2 60 of Fig. 3 looking in the direction indicated by the arrows but showing parts of the supporting frame and propelling mechanism removed.

Fig. 6 is a detailed view of a portion of 65 one of the legs of the horse showing the means for connecting the parts thereof together at its joints.

Fig. 7 is a cross-sectional view of a modified form of the body of the horse but with 70 the interior mechanism thereof removed, and

Fig. 8 is a bottom plan view thereof.

Like numerals of reference refer to corresponding parts throughout the different 75 views of the drawings.

Referring now more particularly to Figs 1 to 6 inclusive of the drawings, the reference numeral 10 designates the base or lower portion of the supporting frame which as 80 shown in Figs. 1, 2 and 3 is in the form of a long narrow bar having at its rear end a pair of prongs 11 on which is horizontally and transversely mounted an axle 12 for the rear wheels 13 of said frame, which are 85 journaled on said axle near its ends. Rigidly mounted on the axle 12 between the prongs 11 of the frame 10 is a sprocket wheel 14 around which is extended a sprocket chain 15 which also passes around a sprocket wheel 90 16 located at a point about the longitudinal middle of the lower portion of the body of the horse and mounted in the manner to be presently explained.

The front portion of the base 10 of the 95 supporting frame is extended upwardly and forwardly as at 17 and is provided at its front end with a downwardly extended buffer or fender 18. Vertically journaled in the front portion of the base 10 is a steering post 19 which has in its lower portion a pair of spaced apart prongs 20 between which is mounted on an axle 21 journaled in the lower ends of the prongs 20, a wheel 22 used for supporting the front end of the 100 base 10 and for steering and for turning the vehicle in the desired direction.

Fixed at its lower end to the base 10 near the rear end of the upwardly and forwardly extended portion 17 thereof is a tubular 110 standard 23 which extends upwardly and is rearwardly inclined as is clearly shown in

Figs. 1 and 2 of the drawings. Connected at its front end to the standard 23 at a point about midway between its ends is a brace member 24 which is extended rearwardly in 5 a horizontal plane from the standard 23 and then downwardly in a rearwardly inclined direction as shown in Fig. 2 and has its lower end secured to the upper surface of the base 10 at the front ends or juncture 10 of the forks 11 of said base. The base 10, standard 23 and brace member 24 constitute the main or supporting frame of the vehicle as will be readily understood. The standard 23 is provided in its lower front portion with 15 an opening or semi-circular slot 25 for the reception and operation of a steering rod 26 which is extended through the opening 25 and up through the tubular standard and has at its upper end a handle 27 by means of 20 which it can be turned.

As shown in Figs. 1 and 2 the rod 26 is provided with an elbow 28 at its portion located in the opening 25 and is extended forwardly and pivotally connected at its lower 25 end to a crank 29 on the upper end of the steering post 19 for the front wheel 22 of the vehicle. Mounted on the upper surface of the horizontal portion of the brace member 24 are a pair of spaced apart screw bolts 30 around each of which is a coiled spring 31 which rest at one of their ends on the brace member 24 and at their other ends against the lower surface of a board 32 which is provided near each of its ends with a suitable 35 opening to receive said bolts. The board or member 32 has secured to its lower surface a plate 33 which is provided with a downwardly extended and transversely apertured lug 34 which is located between a pair of upwardly extended and transversely apertured lugs 35 on a plate 36 secured on the upper surface of the horizontal portion of the brace member 24. A pivot 37 is extended 40 through the apertures of the lugs 34 and 35 and thus pivotally connects them together so as to permit of a tilting movement of the board 32 longitudinally with respect to the supporting frame, the springs 31 yielding sufficiently to permit of such movement at 45 the desired time.

By reference to Fig. 4 of the drawings, it will be seen that the brace member 24 is quite narrow while the board 32 is of sufficient width to rest against the inner surfaces of the sides of the body of the horse where it may be secured by any suitable means.

Secured to the lower surface of the horizontal portion of the brace member 24 directly under the plate 36 thereon is a depending hanger 38 in which is transversely journaled a shaft 39 on which is mounted near one side of the hanger 38 a sprocket wheel 40 over which a sprocket chain 41 passes, 60 65 which chain also passes over a sprocket

wheel 42 mounted on a pedal or crank shaft 43. This shaft 43 is transversely journaled on a depending hanger 44 which is mounted at its upper end on the lower surface of the horizontal portion 24 of the brace member 70 and straddles the hanger 38 as is clearly shown in Fig. 2 of the drawings, in which view, as well as in Figs. 1, 4 and 5 it will be seen that the crank or pedal shaft 43 is located transversely at the lower middle portion of 75 the body of the horse and has at each of its ends a crank 45, each of which is by preference provided with a pedal 46 or foot rest for the feet of the child or rider of the horse.

The shaft 39 unites the opposite sides of 80 the body of the horse and may be suitably secured thereto so as to assist the tilting member 32 in holding said sides together. The sprocket wheel 16 above referred to is mounted on the shaft 43 between the 85 sprocket wheel 42 and the hanger 44, and is geared to the sprocket wheel 14 on the rear axle by means of the sprocket chain 15 as is clearly shown in Figs. 2 and 4 of the drawings.

The body and neck of the horse, in the present instance, is shown as consisting of two side pieces 47 and 48 which are counterparts of one another and are fashioned to resemble in outlines the figure of a miniature 85 horse or pony. These side pieces 47 and 48 may be made of any suitable material such as papier mâché and hollowed on their inner surfaces as shown to afford when joined together at their meeting edges a housing for 100 that part of the propelling mechanism located therein.

It will be understood that the edges of the upper part of the side pieces 47 and 48 of the body of the horse, as well as the lower edges or belly portion 49 thereof, will meet and may be secured together by cement or otherwise after they have been placed on the supporting frame of the vehicle. In order to provide means for the operation of 105 the drive chain 15 and for the reception of the upwardly extended standard 23 and the upwardly extended portion of the brace member 24 the lower meeting edge of each of the side pieces 47 and 48 is provided with 110 cut-away portions 50, 51, and 52 for the said parts respectively, which construction is clearly shown in Fig. 2 of the drawings. The tubular standard 23 extends at its upper end through a suitable opening 53 in the 115 upper part of the neck of the horse and may be secured in said opening in any suitable manner.

It will be observed by reference to the last named figure that the openings 50, 51 and 52 in the lower portion of the body of the horse or in the meeting edges of the sides thereof are of sufficient size to permit of slight longitudinally tilting movement of the body of the horse on the pivot 37 of the 120 125 130

tilting member 32 which is provided for this purpose.

By further reference to Fig. 2 of the drawings, it will be seen and understood that the upper end of the neck portion of each of the side members 47 and 48 is provided with a rounded and forward extension 54 to fit in segmental recesses 55 with which the inner surface of each side of the head 56 of the horse is provided at their rear ends or portions adjacent to the upper ends of the neck portion of the horse. The head 56 is secured by means of a pivot 57 to the upper portion of the neck, which pivot is transversely extended through the side portions of the neck and the rear portions of the sides of the head as is clearly shown. A spring 58 is attached at one of its ends to one or both of the projections 54 and at its other end to the upper portion of the head 56 within the cavity thereof. By this arrangement it is apparent that in the tilting or rocking movement of the body of the horse, the head 56 will have a slight pivotal or up and down movement.

Each of the side pieces 47 and 48 is provided on its outer surface near its front and rear lower portions with a circular recess or socket 59 each of which has by preference its surrounding walls inwardly beveled as shown in Fig. 3 to receive correspondingly beveled circular portions 60 on the upper portions of the legs of the horse. Each of the front legs of the horse is by preference made of an upper piece 61 and a lower piece 62, while the rear legs are by preference made of a single piece 63 fashioned in the shape of the hind leg of such an animal. The circular portion 60 of each of the front legs is pivotally secured to the sides 47 and 48 of the body of the horse adjacent thereto by means of a pivot 64 which is centrally located therein as well as in the circular socket or depression 59 for said portion of the leg.

Each of the circular portions 60 of the hind legs 63 is similarly secured to the sides of the body of the horse by means of pivots 64 located centrally in said portions of said legs as well as centrally in the sockets 59 therefor. Thus it will be understood that the front and rear legs of the horse will normally depend on either side of the base 10 of the supporting frame and in such a way as not to be interfered therewith in their movements. Each of the circular portions of each of the legs is provided with an inwardly extended pin 65 which are located eccentrically with respect to the pivots of said legs and said pins are extended through suitable segmental slots 66 in the recessed portions 59 of the sides of the body of the horse as is clearly shown in Figs. 3 and 5 of the drawings.

65 Mounted on the shaft 39 near the inner

surface of each of the sides 47 and 48 of the body of the horse is an eccentric disk 67 each of which is surrounded by a band 68 which has an arm 69 extended therefrom, each of said arms being provided with a slot 70 for the reception of pins 71 used for loosely uniting said arms to connecting bars or members 72 and 73 one of which is connected at its ends by means of the pivot pins 65 to the circular portion 60 of the front leg of the horse on one side of the body thereof and to the circular portion 60 of the hind leg on the opposite side of the body, while the other of said bars is similarly connected by like means to the circular part of the other front leg and the circular part of the other hind leg. To provide for the operation of the bars 72 and 73 without interference by other parts of the inclosed mechanism they are formed of an irregular shape, as shown in Figs. 2 to 5 inclusive in which views it will be observed that said bars or connections extend crosswise of the body and above and below the shaft 39 on which the eccentrics are mounted.

In order to prevent the lower portions 62 of the front legs moving upwardly too far on their pivots with the upper portions 61 of said legs and thus produce a distorted effect, the lower portion of each of the parts 61 of said legs is provided with a downwardly extended recess 74 to receive a tongue 75 on the upper portion of the lower part 62 which is secured to the lower portion of the upper part 61 by means of a pivot 76 all of which will be clearly understood by reference to Fig. 6 of the drawings.

In Figs. 7 and 8 I have shown a modification in the construction of the body of the horse which consists of five pieces instead of two pieces as in the above described construction. In this modified form the sides of the body consist of two flat members 47^a and 48^a, a rounded top member 77, and a bottom or belly member of two pieces 78 and 79 located side by side and secured to the lower edges of the side members 47^a and 48^a by means of nails, screws or otherwise. The pieces 78 and 79 are formed at their meeting edges with cut-away portions 80, 81 and 82 for the operation and reception of the sprocket wheel 16 and its chain 15 and the tubular standard 23 and upwardly extended portion of the brace member 24 respectively. The upper portion 77 of the body and neck of the horse is secured near its edges to the sides 47^a and 48^a by means of nails or screws 83 or otherwise, and the front and rear ends of the members 47^a and 48^a are connected together by suitably fashioned end pieces 84 and 85 which may be secured to the side pieces by any suitable means.

In this modified form it will be understood that the side pieces 47^a and 48^a can

be provided in their outer surfaces with circular depressions like those indicated by the reference numeral 59 in other views of the drawings, and for a like purpose. The 5 operating mechanism used in the modified construction is the same as that used in the first described construction, and for this reason it is deemed unnecessary to illustrate the same or to further describe it.

10 From the foregoing, and by reference to the drawings, it will be understood that a saddle 86 may be fixed in the proper position on the back of the body of the horse to provide a comfortable seat for the user 15 directly above the pedals 46 of the crank or pedal shaft.

In the operation of the vehicle the child 20 will sit astride the saddle 86 and place his feet on the pedals 46 when by pressing forwardly and downwardly on said pedals alternately, it is manifest that the rear wheels 13 of the vehicle will be caused to rotate and thus propel the frame and its mountings. In the operation of propelling the 25 vehicle, it is obvious that the front and rear legs on opposite sides of the body of the horse will be moved back and forth alternately in pairs similar to the life-like movement and that by reason of the jointed connection of the parts 61 and 62 of the front legs the natural movement of said legs will be closely simulated. The pivoted and 30 spring actuated head 56 in the operation of the vehicle will be caused to move up and down or in a slight nodding way. As the 35 tilting member 32 is fixed to the body of the horse and is pivotally mounted on the horizontal portion of the brace member 24 it is manifest that the body of the horse 40 will have a longitudinal rocking or tilting movement as a further simulation of the movement of a natural horse.

A tail 87 of horse hair or other suitable material and having at its front portion a 45 body or plug 88 may be secured to the rear upper portion of the body by inserting said plug or body into a socket 89 provided for this purpose.

Having thus fully described my invention, 50 what I claim as new and desire to secure by Letters Patent is—

1. In a device of the class described, the combination with a supporting frame including a wheeled base and a support extended upwardly therefrom, of a crank shaft transversely supported by the upper portion of said support below the same, gearing uniting said shaft and the axle of the rear wheels of the main frame for driving said wheels, a 55 body in simulation of the body of a horse mounted on the said support for pivotal movement longitudinally with respect to the support, a pair of legs pivotally mounted on each side of said body, means operatively connecting the diagonally disposed legs in 60 65

pairs, and means driven by the crank shaft and connected to said operative connections with the legs for imparting pivotal movement to the latter.

2. In a device of the class described, the combination with a supporting frame including a wheeled base and a support extended upwardly therefrom, of a crank shaft transversely supported by the upper portion of said support below the same, means uniting said shaft and axle of the rear wheels of the main frame for turning said wheels and propelling said frame, a body in simulation of the body of a horse mounted on the said support for pivotal movement longitudinally with respect thereto, a pair of legs depending from the front and rear portions of each side of said body, and operative means connecting said legs with the crank shaft for imparting pivotal movement to the diagonally disposed legs in pairs. 70 75 80

3. In a device of the class described, the combination with a supporting frame including a wheeled base and a support extended upwardly therefrom, of a crank shaft transversely supported by the upper portion of said support below the same, means uniting said shaft and axle of the rear wheels of the main frame for turning said wheels and propelling said frame, a body in simulation 90 of the body of a horse mounted on the said support for pivotal movement longitudinally with respect thereto, a pair of legs depending from the front and rear portions of each side of said body, operative means connecting said legs with the crank shaft for imparting pivotal movement to the diagonally disposed legs in pairs, and a spring actuated head pivotally mounted on the upper portion of the neck part of said body. 95 100 105

4. In a device of the class described, the combination with a supporting frame including a horizontally disposed base and a support extended upwardly therefrom, of a drive shaft transversely journaled on the rear part of said base, a wheel on each end of said drive shaft, a steering post vertically journaled in the front portion of said base, a wheel journaled on said post, a crank shaft transversely supported by the upper portion 110 of the support of the main frame, gearing uniting said crank shaft and the drive shaft, a spring actuated horizontally disposed member pivotally mounted on the support of the main frame, a body in simulation 115 of the body of a horse mounted on said support and inclosing said pivoted member and the upper portion of said support, said body being secured to said pivoted member to move therewith, a shaft transversely journaled above the crank shaft on said support, a pair of legs pivotally mounted on each side of said body, connections operatively connecting the diagonally disposed legs in pairs, means connecting the last named shaft 120 125 130

to said connections of the legs to impart pivotal movement to the diagonally disposed legs in pairs, operative means connecting the last named shaft to the crank shaft, and a steering rod connected at one of its ends to the steering post and extended upwardly through the said body.

5. In a device of the class described, the combination with a supporting frame including a horizontally disposed base and a support extended upwardly therefrom, of a drive shaft transversely journaled on the rear portion of said base, a pair of wheels on said drive shaft, a steering post vertically journaled in the front portion of the base, a wheel mounted on said post, a crank shaft transversely journaled on the upper portion

of the support of the main frame but below said portion, means connecting the crank shaft and the drive shaft for transmitting 20 rotary motion from the former to the latter, a horizontally disposed member pivotally mounted on the upper portion of the support of the main frame, a transversely disposed shaft mounted on said support above 25 the crank shaft, gearing uniting said shafts, a body in simulation of the body of a horse inclosing said pivoted member and secured to the same and terminating above the crank shaft, and a steering rod connected at one 30 of its ends to the steering post and extended upwardly through the front portion of the body.

IR A. BURNETT.
